Primary Examiner — Janice Hallmark(74) *Attorney, Agent, or Firm* — LegalForce RAPC Worldwide**CLAIM**

The ornamental design for a spray bottle fan, as shown and described.

DESCRIPTION

FIG. 1 is a front left side perspective view for a spray bottle fan, showing our new design;

FIG. 2 is a front elevational view of FIG. 1 thereof;

FIG. 3 is a rear elevational view of FIG. 1 thereof;

FIG. 4 is a left side elevational view of FIG. 1 thereof;

FIG. 5 is a right side elevational view of FIG. 1 thereof; and,

FIG. 6 is a top plan view of FIG. 1 thereof.

The broken lines indicate unclaimed portions of the design and form no part of the claimed design.

1 Claim, 6 Drawing Sheets(56)
